UNITED STATES PATENT OFFICE.

EDGAR B. SYMONS, OF MILWAUKEE, WISCONSIN.

PULSATING SCREEN.

1,141,153.

Specification of Letters Patent. Patented June 1, 1915.

Application filed February 7, 1913. Serial No. 746,695.

To all whom it may concern:

Be it known that I, EDGAR B. SYMONS, a citizen of the United States, residing at Milwaukee, in the county of Milwaukee and State of Wisconsin, have invented a certain new and useful Improvement in Pulsating Screens, of which the following is a specification.

My invention relates to improvements in pulsating screens and, while pulsating screens themselves have long been known, it has many marked features of superiority to the general run of such devices. Among these features of superiority one is that in the ordinary shaker or pulsating screen the movement in either direction is equally rapid. The consequence is that the stone is tossed in the air and, before it has time to settle, the screen comes up and again strikes it throwing it farther up so that the movement of the material in the screen is very great and the opportunity for settling and separating is very small as, instead of occurring during the period while the stone is at rest it only occurs at that instant when the stone is being violently struck by the screen and the stone thus has no time to settle on the screen and fall through the perforations before the next upward toss. In my device I provide means whereby the upward toss is relatively rapid and violent while the downward retraction or downward movement is comparatively slow, thus giving ample time for this settling and sifting of the material which is so necessary.

Another advantage of my device is that by means of the spring supports there are none of the ordinary hanger bearings to knock and rattle and get stiff and wear out. Also the pressure on the drive bearings is always in one direction. There is no reciprocating movement inside of the bearing such as might and so frequently does ruin them.

My invention is illustrated diagrammatically in one form in the accompanying drawings, wherein—

Figure 1 is a plan view with parts broken away; Fig. 2 is a section along the line 2—2 of Fig. 1 with parts broken away; Fig. 3 is a section along the line 3—3 of Fig. 1.

Like parts are indicated by like letters throughout the several figures.

A is a supporting frame or base open at top and bottom.

A¹ is a hopper mounted thereon. 55

A² is a feed chute discharging into the hopper.

A³ is a feed supply discharging from the hopper.

B is a pulsating frame open at top and bottom, partially closed at the bottom by the screen B¹.

B² is a scoop or chute pivotally mounted on and extending across one end of the pulsating frame B and discharging downwardly 65 toward the screen B¹ adapted to receive the discharge from the supply A³.

B³ is a screw-threaded member provided with adjusting nuts B⁴ in engagement with the lugs B⁵ on the frame B and chute B² 70 whereby the angle of inclination of the chute may be controlled or adjusted.

C C are hangers rigidly attached to the frame or base A.

C¹ C¹ are hangers rigidly attached to the 75 pulsating frame B.

C² C² are supporting and throwing springs rigidly attached to the hangers C C and C¹ C¹.

D is a housing mounted on the bearing 80 frame D¹.

The bearing frames D¹ and D² are each supported on the frame or base A.

D³ is a rock shaft rotatably mounted in the bearings D⁴ D⁵ on the bearing frames D² D¹ 85 respectively.

D⁶ D⁶ are rocker arms keyed to the shaft D³ adjacent each side of the frame B.

D⁷ D⁷ are brackets or hangers rigidly attached to the side of the frame B and in 90 pivotal connection with the rocker arms D⁶ D⁶.

D⁸ D⁸ are fingers projecting upwardly and forwardly from the hangers D⁷ D⁷.

E is a tie rod supported at either end on 95 one of the frames D¹ D².

E¹ E¹ are cup washers resting upon said tie rod E and surrounding and in slidably contact with the rods E² E² which are in slidably engagement with the tie rod E and 100

terminate in the hooks E^3 E^3 in hooked engagement with the fingers D^8 .

E^4 E^4 are cup washers mounted on the free ends of the rods E^2 E^2 held in adjustable position thereon by means of the nuts E^5 E^5 .

The springs E^6 surround the rods or bars E^2 and are in engagement at either end with one of the washers E^1 E^4 adapted to be constricted between these washers when the rods E^2 are drawn inwardly toward the screen.

F is a cam or drive shaft rigidly mounted in the bearings F^1 F^2 on the frames D^2 D^1 .

F^3 is a driving pulley rigidly attached to the shaft F and adapted to be driven by any suitable source of power not shown.

F^4 is a four-point cam rigidly attached to the shaft F .

F^5 is a rocker arm rigidly attached to the rock shaft D^3 having the contact block F^6 in engagement with the cam F^4 .

F^7 is a filling opening whereby the housing D may be filled with grease.

F^8 is a discharge opening whereby it may be emptied or drained.

Referring to the cam F^4 it will be noted that the angle a is substantially one-half of the angle b and that the cam rotates in the direction indicated by the arrow. It will be further noted that when the device is in the normal, upright or raised position as indicated in Fig. 2 the spring C^2 is substantially parallel with the crank D^6 .

It will be evident that, while I have shown in my drawings an operative device, still many changes might be made in size, shape and arrangement of parts without departing materially from the spirit of my invention and I wish therefore that my drawings be regarded as in a sense diagrammatic.

The use and operation of my invention are as follows:—With the parts in the assembled position as indicated in the drawings the housing or casing is first substantially filled with heavy oil or grease. The machine is then started the cam rotating in the direction of the arrow. It will be noted that with the parts in the position shown in Fig. 3 as the cam rotates the block or pillow F^6 will move rapidly inward toward the center of the cam shaft until the point x has been reached. It will then gradually be forced out until it reaches the point y . It will then rapidly return to the inside position until the point z is reached. This process will continue as long as the cam is rotated. It will be noted that the angular distance traversed between the points x y and z q is substantially twice as great as the angular distance traversed between the points k x and y z so that the upward movement caused by the spring will be twice as rapid as the downward movement against the spring caused by the rotation of the cam. The ro-

tation of the cam will, of course, rock the rock shaft and cause the rocker arms to rotate depressing the screen but also pressing it backward so that the screen, when acted upon by the spring will be shot forward and upward and the material on the screen will also be shot forward and upward. This will result in projecting the material which is supported on the surface of the screen forward and upward and gradually carrying it over to the open end. The long time during which the screen is being forced down gives ample time for the material to settle on the screen and be sifted through it instead of being batted up by the screen while still in the air and before being sifted, and as the screen pulsates the material will be thrown up diagonally and allowed to settle vertically under the influence of gravity, thus the material is being constantly agitated and tossed upward, the finer particles being sifted out. The weight of the screen and contents is of course all supported by the spring so that the sole function of the rocker arms and the cam shaft is to depress the whole mass against the tension of the springs and as this work is done slowly and evenly the load upon the bearings and upon the machinery is very slight, the violent jerking being done by the springs which are not likely to be harmed by it instead of being done by bearings which would be very materially harmed.

I claim:

1. A screen comprising a perforated fabric, a frame to support the same, means for feeding the material to be screened onto one end of such fabric, means for confining the fabric during operation to planes parallel one to the other and means for moving it bodily swiftly upwardly and longitudinally away from the feed and slowly in the reverse direction.

2. A screen comprising a perforated fabric, a frame to support the same, means for feeding the material to be screened onto one end of such fabric, and means for moving it bodily swiftly upwardly and longitudinally away from the feed and slowly in the reverse direction, such motion equal at both ends.

3. A screen comprising a perforated fabric located in a substantially horizontal plane, a frame to support the same, means for feeding the material to be screened onto one end of such fabric and elastic supporting devices, one at each end of the fabric frame and both adapted to give a vertical and horizontal motion to the end of the frame with which it is associated.

4. A screen comprising a perforated fabric, a frame to support the same, means for feeding the material to be screened onto one end of such fabric, a spring support for each

end of the fabric frame adapted to impart both vertical and horizontal motion to the end of the frame with which it is associated and means for moving the frame downwardly and rearwardly in the direction toward the feed and to release it so that said springs may move it swiftly upwardly and forwardly away from the feed.

In testimony whereof, I affix my signature in the presence of two witnesses this 3 day 10 of February 1913.

EDGAR B. SYMONS.
